UNITED STATES PATENT OFFICE.

ELZA H. REITER, OF ELGIN, ILLINOIS.

FLUE-CLEANER.

1,112,322.

Specification of Letters Patent. Patented Sept. 29, 1914.

Application filed June 3, 1912. Serial No. 701,343.

To all whom it may concern:

Be it known that I, ELZA H. REITER, a citizen of the United States, residing at Elgin, in the county of Kane, State of Illinois, have invented certain new and useful improvements in Flue-Cleaners; and I do hereby declare the following to be a full, clear, and exact description of the invention, such as will enable others skilled in the art 10 to which it appertains to make and use the same.

The present invention relates to certain novel and useful improvements in a device for cleaning boiler flues and is in the nature of an improvement on the subject matter of my patent for flue cleaner, Number 966,051, dated Aug. 2, 1910. This invention has particular application to a structure adapted to be connected to the doors of return flue boilers whereby the cleaning operation may be thoroughly and rapidly accomplished without the necessity of opening the doors.

Still a further object of my invention is to 25 simplify and improve the construction and increase the efficiency and utility of devices of this character.

I also aim to provide an attachment whereby each individual flue of the boiler 30 may be reached from a plurality of points, in the present instance two in number, so that the cleaning operation may be speedily and conveniently accomplished.

It is also my purpose to provide a cleaning device wherein the elements constituting the same may be adjusted to such positions as the circumstances may demand, and furthermore I propose to provide a device which will embody the desired features of 40 simplicity and durability coupled with cheapness of cost in manufacture, sale and installation.

With the above recited objects and others of a similar nature in view my invention 45 consists in the construction, combination and arrangement of parts set forth in and falling within the scope of the appended claim.

In the accompanying drawing like characters of reference indicate like parts in all the views, and,

Figure 1 is a sectional side elevation of the front portion of a boiler and illustrating the application of my invention. Fig. 2 is a 55 front elevation of the device detached. Fig. 3 is a cross sectional view taken on the line

3—3 of Fig. 2. Fig. 4 is a sectional view on the line 4—4 of Fig. 2.

Referring now to the accompanying drawing in detail, the letter A indicates conventionally a boiler of any approved type of which 1 is the front thereof, 2—2 a front door and 3 the tubes or flues.

Each of the doors is provided with an adjustable supporting attachment for the 60 blower or cleaning device proper, and as these attachments are similar in construction a description of one will suffice for all. Each door is provided approximately centrally with an aperture 4 through which is designed to project the tubular member of the blower, said opening being preferably provided with a pivoted closure plate 5.

The numeral 6 indicates as an entirety a 65 U-shaped frame having a notched or serrated cross bar 7, while the parallel arms 8—8 of said frame are provided at their free ends with bolt holes 9 designed to receive the shank portions 10 of the angular hinged bolts 11, the shanks 12 of said bolts projecting through the adjacent portions of the 70 wall of the flue cap door and are held in place thereto by the nuts 13, while the nuts 14 are employed to pivotally hold the frame 75 in position on the shanks 10.

The notched bar 7 of each frame is provided, preferably centrally thereof, with an aperture 15 for the passage of the threaded shank 16 of the curved or segmental bar 17. The shank is provided with the adjustable 80 nuts 18—18 by means of which the length of the bar may be adjusted to slightly raise or lower the inner end of the blow pipe to strike the tube or flue at the proper point. Furthermore the aperture 15 is slightly 85 elongated and enough larger than the threaded shank 16 to permit of the latter having sufficient lost motion to play loosely in such aperture thereby allowing the weight of the bar 17 to cause it to drag on the lower 90 edge wall of the slot 19 formed in the door and through which the bar projects. It will be noted that the segmental bar is provided at its under edge with a plurality of teeth or serrations 20 designed to engage with the 95 lower edge wall of the aperture 19 so that the bar may be adjusted to any required extent within the range of the teeth or notches, thus correspondingly adjusting the U-shaped frame 6. Furthermore, it will be 100 noted that while the segmental toothed or notched bar is carried by the U-shaped

frame, it, at the same time performs the function of supporting said frame in any desired position of vertical adjustment within range of the notched portion.

5 The cleaning device or blower proper, which in the present instance is merely conventionally illustrated, comprises the blow pipe 21 to which is connected one end of the hose 22, the opposite end of the hose being attached as at 23 to the steam pipe 24.

From the above description taken in connection with the accompanying drawing the construction and operation of my improved device will be readily apparent. In operation the doors being closed, the segmental bar is first adjusted to locate the U-shaped cross bar in proper position to hold the blow pipe pointed toward the row of flues in which it is desired to operate and the pipe

20 is then passed through the aperture 4 in the closed door and the inner end of the pipe inserted into one of the flues. The steam is then admitted through the blower, passing through the tube from the front to the rear, 25 and thoroughly cleaning the soot or other products of combustion without exposing the boiler head and drawing the cold air in with the steam. Thus while blowing one tube, the draft is on all the other tubes and

30 the hot gases are drawn in with the steam practically super-heating the latter and eliminating the moisture therefrom. It will be further noted from the present drawing and description that the blower may be

35 operated at either door opposite the center of the tube area thus blowing half the tubes from the center of each door. It will be further seen that as the cleaner is operated while the doors are closed, the bank of tubes

40 may be cleaned without checking the draft or interrupting the service of the boiler. In practice the bars 7 are provided with notches corresponding to the number of tubes in each horizontal row of the tube bank so that when the device is in operation the shifting of the blower tube from one notch of the bar 7 to the next notch also shifts the inner end of the blower from one tube to the adjacent tube of the row.

45 I am aware of the fact that hitherto it has been proposed to support a flue blower pipe on the furnace in position to afford the end of the pipe access to the flue. But in all such instances, with which I am acquainted it

has been necessary to form a relatively large 55 special opening in the wall of the boiler setting, usually the rear wall, and install in said opening a specially constructed frame which carries the supporting mechanism of the blower pipe or flue cleaner proper. 60 Such a construction is illustrated in my earlier patent hereinbefore mentioned. In the present instance however, by forming a special opening in the flue door at the front of the boiler I am enabled to blow the tubes 65 from the front or the rear while the doors are closed so that there is no interference with the draft or service of the boiler. Furthermore I obviate the expense and disadvantage of breaking the wall of the boiler 70 setting and installing the frame and other parts therein.

While I have herein shown and described one particular embodiment of my invention, I wish it to be understood that I do not 75 confine myself to all of the precise details of construction herein set forth by way of illustration, as modification and variation may be made without departing from the spirit of the invention or exceeding the scope of 80 the appended claim.

What I claim is:

The combination with a flue door formed with an opening therein for the passage of a tube cleaning device and a second opening 85 for the passage of a segmental rack bar, of a tube cleaning device, a support for said device comprising a U-shaped frame, angular bolts pivotally connecting the leg portions of the frame to the door and at opposite 90 sides of the first mentioned opening, so that the frame may swing freely on the angular bolts, a segmental rack bar adapted to adjustably engage with the wall of the second opening in the flue door, said bar having a 95 shank projecting through a relatively large aperture in the cross bar of the U-shaped frame so that said shank may have a limited amount of play in the aperture, and means for adjustably securing the shank portion of 100 the rack bar to the cross bar of the frame.

In testimony whereof, I affix my signature, in presence of two witnesses.

ELZA H. REITER.
